UNITED STATES PATENT OFFICE.

MONTAGUE H. ROBERTS, OF ENGLEWOOD, NEW JERSEY, ASSIGNOR TO FRANKLIN
RAILWAY SUPPLY COMPANY, A CORPORATION OF DELAWARE.

LOCOMOTIVE-BOOSTER APPARATUS.

Application filed October 3, 1922. Serial No. 592,003.

This invention relates to locomotive booster apparatus and it has for its primary object the provision of improvements whereby certain difficulties, specifically pointed out hereinafter, are overcome. The foregoing, together with such other objects as may hereinafter appear or are incident to my invention, I obtain by means of a construction which I have illustrated in 10 preferred form in the accompanying drawings, wherein:

Fig. 1 is a partial plan and sectional view of a locomotive booster illustrating the application of my improvements thereto; Fig. 15 2 is an enlarged section taken on the line 2—2 of Fig. 1; and Fig. 3 is a section taken on the line 3—3 of Fig. 1.

Referring now to Fig. 1, the booster engine apparatus, indicated as a whole by the 20 reference letter A, is, in part, supported on the axle 7 of a truck, such for example, as the trailing truck of a locomotive, and in part either on some other portion of the truck or from the locomotive structure.

25 The booster comprises, inter alia, the bed plate 8 which, together with such members as the top or cover plate 9, the side plate 10 and the plate 11, constituting a closed, oil-tight casing, which houses the working parts such as the gearing B for driving the axle 7, the connecting rod or crank arm C, the valve motions D, etc. These working parts are 30 preferably lubricated by a splash system and the casing, therefore, is intended to contain a sufficient quantity of oil at all times for 35 this purpose.

The cylinders and valve chests, indicated by the reference letter E, are secured to the rear end of the casing, the piston rods 12, 40 of course, extending into the casing and being provided with cross heads 13. The valves 14 are preferably of the piston type and the rods 15 therefore, also extend into the casing for connection with the valve motions D.

45 Steam is supplied to the valve chest from the locomotive boiler in any preferred manner as by means of the steam pipe or pipes 16 and the exhaust steam is lead to a suitable point by means of the exhaust pipe 17.

One of the difficulties encountered in connection with the apparatus thus generally described, is that condensate from the valve chests and cylinders is apt to work into the 50 casing and mingle with the oil and produce

detrimental results. It is practically impossible to provide packings which will not either leak or permit condensate to work past without producing a binding action on the pistons and rods and even if it were 60 possible to make them sufficiently tight for this purpose, the wear would in a short time make them leaky. I overcome this difficulty in the following manner:

Referring now first to the rods 15 for the 65 piston valves 14, I provide a cap member 18 over the openings 19 in the chest through which the rods extend. A wire gasket 20 is interposed between each cap and the valve chest and the cap is held in place as by 70 means of the studs 20', indicated in Fig. 3. The head of the cap is, of course, apertured for passage of the rod and it is provided with a neck 21 on which the packing gland member 22 is threaded. There is also an annular groove 23 formed in the head from 75 which the pipe 24 leads to a discharge pipe 25 which discharges to the atmosphere. Within the cap 18 I provide the wipe packing F, the construction of which is clearly 80 shown in Fig. 2. This packing is always held in tight condition by the spring 26.

It will be seen, therefore, that the valve rods have two packings between which there is a vent to the atmosphere. Any leakage 85 past the packing F will thus vent itself to the atmosphere and none will pass the packing gland 22, in which connection it will be borne in mind that there is no pressure on the packing of this gland because of the interposed vent to the atmosphere.

With reference to the piston rods 12, it will be seen that in all material respects a similar arrangement is provided to prevent leakage into the casing. As before, two 90 spaced packings F and 22' are provided and at a point intermediate the two there is an annular chamber or space 23. It is unnecessary, however, to provide vent pipes, the port 23' (see Fig. 2) serving the same purpose.

What I claim is:

1. In combination, a locomotive booster mechanism including a steam chamber, a piston operating within said chamber, an engine casing operatively associated with said steam chamber for housing a driving mechanism actuated by said piston, said driving mechanism operating in a bath of lubricant contained within said engine casing, 100

and means for effectually precluding the passage of steam into said engine casing at the same time that it effectually prevents the leakage of the lubricant therefrom.

5. 2. In combination, a locomotive booster mechanism including a piston chamber and a valve chamber for controlling the supply of steam to said piston chamber, a casing for housing a driving mechanism actuated 10 by the piston and valve, said driving mechanism being operated in a bath of oil contained in said casing, and means operatively associated with said mechanism for commonly preventing the passage of steam into 15 said oil casing and for preventing the leakage of oil therefrom.

3. In combination, a booster mechanism including a steam chamber, a driving mechanism operated thereby including an oil casing disposed adjacent said steam chamber, the opposed faces of said chamber and casing being provided with aligned openings through which a rod reciprocates, and means associated with that portion of said rod 25 which extends between said openings for commonly preventing the escape of steam from the steam chamber and oil from the oil casing.

4. In combination, a booster mechanism 30 including a steam chamber, a driving mechanism operated thereby including an oil casing, said chamber and casing being disposed adjacent one another and being provided with registering openings through

which a moving element reciprocates and a seal surrounding said moving element in the vicinity of said openings for effectually preventing the leakage of oil from the casing, said seal being further arranged to vent any escaped steam from the steam chamber to 40 the atmosphere.

5. In combination, a booster mechanism including piston and valve chambers, an oil casing disposed adjacent said chambers, a piston and a valve arranged within said 45 chambers, respectively, for operative connection with a driving mechanism housed within said oil casing, and means for preventing the leakage of oil from said oil casing and the passage of steam from said chambers into said casing.

6. In combination, a booster mechanism including piston and valve chambers, an oil casing disposed adjacent said chambers, a piston and a valve arranged within said 55 chambers, respectively, for operative connection with a driving mechanism housed within said oil casing, and a pair of seals for preventing the leakage of oil from said oil casing and the passage of steam from said 60 chambers into said casing, one of said seals being disposed entirely within said oil casing and the other thereof being disposed intermediate said oil casing and one of said steam chambers.

In testimony whereof, I have hereunto signed my name.

MONTAGUE H. ROBERTS.

DISCLAIMER

1,647,146.—*Montague H. Roberts*, Englewood, N. J. LOCOMOTIVE-BOOSTER APPARATUS. Patent dated November 1, 1927. Disclaimer filed April 5, 1933, by the assignee, *Franklin Railway Supply Company*.

Hereby enters this disclaimer to that part of the claims in said specification which is in the following words, to wit:

“1. In combination, a locomotive booster mechanism including a steam chamber, a piston operating within said chamber, an engine casing operatively associated with said steam chamber for housing a driving mechanism actuated by said piston, said driving mechanism operating in a bath of lubricant contained within said engine casing, and means for effectually precluding the passage of steam into said engine casing at the same time that it effectually prevents the leakage of the lubricant therefrom.

“2. In combination, a locomotive booster mechanism including a piston chamber and a valve chamber for controlling the supply of steam to said piston chamber, a casing for housing a driving mechanism actuated by the piston and valve, said driving mechanism being operated in a bath of oil contained in said casing, and means operatively associated with said mechanism for commonly preventing the passage of steam into said oil casing and for preventing leakage of oil therefrom.

“3. In combination, a booster mechanism including a steam chamber, a driving mechanism operated thereby including an oil casing disposed adjacent said steam chamber, the opposed faces of said chamber and casing being provided with aligned openings through which a rod reciprocates, and means associated with that portion of said rod which extends between said openings for commonly preventing the escape of steam from the steam chamber and oil from the oil casing.

“4. In combination, a booster mechanism including a steam chamber, a driving mechanism operated thereby including an oil casing, said chamber and casing being disposed adjacent one another and being provided with registering openings through which a moving element reciprocates and a seal surrounding said moving element in the vicinity of said openings for effectually preventing the leakage of oil from the casing, said seal being further arranged to vent any escaped steam from the steam chamber to the atmosphere.

“5. In combination, a booster mechanism including piston and valve chambers, an oil casing disposed adjacent said chambers, a piston and a valve arranged within said chambers, respectively, for operative connection with a driving mechanism housed within said oil casing, and means for preventing the leakage of oil from said oil casing and the passage of steam from said chambers into said casing.”
